TABULATING MACHINE

Eugen Buhler, Binghamton, N. Y., assignor to
 International Business Machines Corporation,
 New York, N. Y., a corporation of New York

Application December 14, 1934, Serial No. 757,461

8 Claims. (Cl. 101—93)

This invention relates to printing mechanisms for accounting machines, in which a plurality of type carriers are provided with a number of types, which are movable to different printing positions. 5 The invention more particularly relates to the suppression of zero printing under certain conditions in printing tabulators and will be described in connection with alphabetical machines of the record card controlled type. The preferred 10 form of printing mechanism, which will be referred to in the following specification, is that in which the type carriers are constantly rotating, and in which printing is effected as the proper type element passes the printing position, without interrupting the rotation of the type carrier. 15

In a record card controlled tabulating machine, perforated record cards are fed into the machine on which data is represented by the location of perforations on the card. These cards 20 are fed at a speed in synchronism with the rotation of the type carriers so that when any one of the sensing brushes of the machine encounters a perforation at a location in the card designating certain data, the corresponding type on the type 25 carrier representing that data will be at its printing position, and electromechanical means initiated by the sensing means will effect the printing of that data. The cards used may be of the well known Hollerith type. A type of 30 printing mechanism adapted to prepare a printed record under control of such types of record cards is fully shown and described in the copending application of Eugen Buhler, Serial No. 712,537, filed February 23, 1934, and in connection with 35 which the present invention finds particular utility.

It is the custom when perforating record cards for these machines to place a perforation in each card column in which numerals are perforated 40 to minimize the risk of inadvertently omitting a significant figure. Thus any column in which no significant figure or digit occurs is punched in the zero position. These latter zero perforations occur to the left of the first significant 45 figure of a number, as well as to the right of it where such a number has a zero in its makeup, but in printing numbers consisting of several different denominational orders, it is desirable to suppress the printing of all zeros to the left of the 50 first left hand significant figure but permitting the printing of zeros to the right of this figure, regardless of their position with respect to any other figure of the number. In the printing of strictly alphabetical items, it is likewise 55 desirable to eliminate all of the zeros.

One of the objects of the present invention is to provide an improved and simplified form of printing mechanism to print either numerals or alphabetical characters, in which mechanism is provided for automatically suppressing the printing of zeros to the left of the first significant figure appearing in a given field of a record card introduced into the machine. 5

Another object is to provide new and improved mechanism for suppressing the printing of zeros 10 appearing in printing of alphabetical items.

Another object is to provide new and improved mechanism for splitting the control of the zero suppression mechanism into groups in order that several numerical items may be printed simultaneously and that the first significant figure of each group will control the suppression of the zeros immediately adjacent and to the right of it, without effecting a numerical item, which may also be to the right of it. 20

There are other objects and advantages of this invention which will be apparent from the specification and the accompanying drawings, which show one embodiment of the invention, and wherein similar reference numerals indicate similar parts. 25

In the drawings:

Fig. 1 is a sectional view to show positional view of parts of the device.

Fig. 2 is a sectional view taken on line 2—2 of 30 Fig. 1.

Fig. 3 is a side elevational view of the device.

Figs. 4 and 5 are detailed views of parts shown in Fig. 1.

Fig. 6 is a partial view of a card showing controlling perforations. 35

Fig. 7 is a detailed view of a modification of the device.

Fig. 8 is a view taken on line 8—8 of Fig. 7.

Fig. 9 is a development of the commutator 40 shown in Fig. 1.

Fig. 10 is a wiring diagram of the machine and shows somewhat diagrammatically some parts of the machine. 45

Referring to Figs. 1 and 3, a shaft 10 is suitably geared to the main drive shaft of the device so as to rotate constantly therewith and make two revolutions for each cycle of operation of the device. Driven from shaft 10 through gearing 11, shaft 12 and gearing 13 is a shaft 14 which 50 has secured thereto a printing drum 15 provided with suitable numerical and alphabetical character types. The constantly rotating drum is provided by suitable gearing to make one revolution for each card cycle. 55

A paper strip 16 is provided and fed past the type by suitable feeding means which is shown and described in my copending application, Serial No. 712,537, filed February 23, 1934. This paper strip is adapted to receive printed records from the type elements 17 and as the feeding and operation of the paper strip play no part in the present invention, it is deemed unnecessary to make any further detailed explanation thereof.

10 In the preferred form of device disclosed herein, in which both alphabet and numerals may be recorded from the perforated cards, single perforations in each column from 0 to 9 represent the numerals and an additional perforation in either the 0, 11, or 12 position causes a zone selecting operation for the purpose of printing alphabetical characters. For example, if a "7" is desired to be represented, a single perforation in the seven index point position would appear, whereas, if the letter "G" was required, perforations would appear in both the 7th and 12th index point positions, in accordance with the code set forth in my previously mentioned copending application. Two sets of brushes are used in the machine, the first set is adapted to sense perforations in the 0, 11, and 12 index point positions to select the zoning in event of alphabetical tabulating. The second set of brushes is adapted to sense perforations in the 0 to 9 index point positions to select the type character.

First taking up the operation of the zoning mechanism. The shaft 10, rotating two revolutions per card cycle, has fixed thereto a gear 18 which drives a gear 20 at the rate of one-half revolution per card cycle through a suitable reduction train of gears 18a.

The gear 20 is fixed to a shaft 21 to which is also fixed a cam 22 (Fig. 3). Cooperating with said cam is a cam follower on the arm 23 of the bell crank lever 24, pivotally mounted at 25 and biased in a counterclockwise direction by the spring 26. By virtue of the cam and spring the bell crank lever 24 is oscillated back and forth once per card cycle. Fixed to the end of the bell crank 24 is a bail 27 extending transversely of the machine and fixed at its opposite end to an identical bell crank lever 24a pivoted at 25a (Figs. 1 and 4). A rod supported at 25 and 25a extends transversely of the machine and pivotally mounted on said rod is a plurality of selecting levers 28, one corresponding to each type carrier and its printing mechanism. These selecting levers are biased against the bail 27 by springs 29 so that whenever any of said levers may be locked against clockwise rotation in a manner to be later explained, the bail 27 may continue to move clockwise under the resilient action of the springs 29. On the bottom edge of the selecting lever 28 are three notches designated 0, 11, and 12 corresponding to the 0, 11, and 12 positions in the record card and the lever 28 is oscillated in such a manner by the bail 27 that on its return or clockwise movement these three notches pass by a projection 30 in synchronism with the movement of the 0, 11, and 12 index point positions on the card by the upper set of brushes 31 (Fig. 10). The projection 30 is integral with a lever 32 pivotally mounted at 33 and biased in a counterclockwise direction by a spring, though normally held out of cooperation with the lever 28 by a pivotally mounted latch 34 which engages one end of the lever 32 by a projection 35 as shown in Fig. 1.

A link 36 is connected to one end of a pivotally mounted armature 37 which is adapted to be ac-

tuated by energization of the magnet 19 to withdraw the latch from cooperation with the lever 32 to permit it to engage the selecting lever 28 in one of the notches such as shown in Fig. 4.

The selecting lever 28 is provided with an integral arm 38 which is provided with three step-like notches 39 (Fig. 4) and is adapted to engage a block 40 fixed to a notched selecting segment 41 and traversing the plane of a disk 42 which is fixed to the shaft 21. There are two selecting segments 41 which are provided with studs passing through elongated apertures in said disk 42 whereby the segments 41 are carried by said disk but are permitted to slide back and forth concentrically in relation to said disk within the limits of the apertures. Springs fastened to the segments at one end and to the disk at another, hold said segments normally in their extreme counterclockwise position in relation to the disk. Pivoted on the disk 42 are pawls 43 which are biased in a counterclockwise direction by suitable springs and are adapted to engage notches in the ends of the selecting segments for the purpose of holding them in a displaced position at selected times. The selecting segments 41 are provided with nine notches 44 so spaced that during the one-half revolution of the disk 42 for each card cycle the notches pass a fixed point in synchronism with the traversal of the index point positions from 9 to 0 as the record card passes the lower brushes 45 (Fig. 10) when the segments are in normal unrestrained position. The notches corresponding to the 0 and 1 positions are continuous and form one single notch being cut away in back of the block 40 as shown at 46 (Fig. 5).

A hooked arm 47 of a T-shaped lever 48 is pivotally located in the plane of the selecting segments with the hooked end adjacent the periphery of the segments. This hooked end constitutes the fixed point previously mentioned by which the notches pass in synchronism with the passage of the index point positions in the record cards by the lower brushes. With the selecting segments unrestrained, the notches pass by the hooked end also in synchronism with the numerical type elements of the printing drum 15, so that should the hook be released to drop into one of the notches it would cause printing to be effected of the numeral corresponding to that notch in a manner to be explained later. Between each numerical type element there are three alphabetical type elements so that in order to select one of the alphabetical type elements the notches would have to be displaced relative to their normal unrestrained position in order that the hooked arm will be delayed in dropping into the notch sufficiently to let the alphabetical type element to be selected arrive at printing position. To effect such displacement performances are punched in the 0, 11 or 12 index point positions. When such a perforation passes the upper brush the magnet 19 becomes energized, unlatching lever 32 to permit the projection 30 to engage one of the notches in the end of lever 28 as previously explained, holding the lever in position for the proper step 39 to catch the block 40 momentarily which retracts the block selector segment 41 against the rotation of disk 42 sufficiently to permit the pawl 43 to engage one of the three notches 44 corresponding to the step 39. Immediately thereafter the bail 50 fixed to shaft 50a is rocked counterclockwise, striking the end of lever 32 and withdrawing the projection 30 from its notch and causing lever 32 to become 75

latched in position by the hook 35 as the magnet 18 is now deenergized.

The spring 29 causes the stepped arm 38 to be withdrawn from cooperation with the block 40. The disk now carries the notched segment in its retracted position now set so the notches pass the hooked arm 47 in synchronism with certain alphabetical characters on the drum 15. The particular one of alphabetical characters selected depends on a record perforation passing the lower brushes which causes the arm 47 to be released to engage its proper notch and effect printing. As the disk 41 continues to rotate a raised edge 51 of the pawl 43 passes adjacent to a bail 52 fixed to a shaft 53 which rocks in a counterclockwise direction depressing the raised edge 51 and retracting pawl 43 from the notch, thus allowing the segment 41 to be restored to its normal position by the springs attached thereto. The shafts 51 and 53 are rocked by means of cam follower arms 54 and 55 respectively which cooperate with cams fixed to shaft 21 suitably shaped and timed to rotate the balls in the proper manner to effect the operations hereinbefore described (Fig. 3).

The release of the T-lever 48 to permit it to engage one of the notches in the segment 41 is effected by energization of magnet 18, through the lower brushes, in a manner to be described later, so that the armature 56 is moved counterclockwise to withdraw latch 57 from holding the lever 58 in the position shown in Fig. 1. When released the lever 58 is turned in a counterclockwise direction by a spring attached thereto whereupon a trip latch or by-pass 59 engages a projection 60 on the T lever 48 and rotates said T lever in a counterclockwise direction urging the hooked arm 47 against the notched segment.

As soon as the hooked arm 47 drops into one of the notches the T lever 47 is rotated still further in a clockwise direction so that the rotation of the T lever causes the arm 61 to cam the latch 62 out of latching cooperation with said arm and simultaneously causing a projection 63 to engage one of the teeth of an actuating wheel 64 which is fixed to the drive shaft 10 and is being constantly rotated in a clockwise direction. This engagement moves the T lever to the right turning the lever 65 in a counterclockwise direction causing the end of it to strike an extension of the printing hammer 66 pivoted at 67, so as to throw it in a clockwise direction about its pivot to strike a blow on the selected type element to effect printing. When the T lever is moved to the right, the projection 60 moves from under the by-pass 59 and the end of the lever strikes a camming surface 68 to positively lift the projection 63 out from engagement with the toothed actuating wheel 64 and the T lever is then moved to the left by means of the spring 69 and is relatched by latch 62, the hooked arm being withdrawn from the notched segment by the positive camming section just mentioned. A bail 70 fixed to shaft 11 restores the lever 58 to its latched position. The timing operation of the bails, latches and actuators are all described in detail in my copending application previously mentioned.

Considering now the elimination of zeros to the left of the left hand significant figure in a card field and the printing of all zeros to the right of said significant figure and falling within the number to be printed. The lever 58 is provided with an arm 72. In the same plane with said lever is an arm of a bell crank lever 73

which is pivoted at 74 and biased in a counterclockwise direction by a spring 75.

The arm 73 normally rests on the arm 72 and is held from rotating thereby. On the opposite end of the bell crank lever 73 is fixed an insulating block 76 to which is attached a right angle contact element 77 (Figs. 1 and 2) in which the horizontal leg of the contact element extends across the plane of the insulating block and the vertical leg extends parallel and adjacent to said block. Two contact elements 78 and 79 adjacent each other normally rest on the horizontal leg of separate contact elements 77, thereby providing an all metal path between two such adjacent contact elements (Fig. 10). If the contact element 78 and insulating block move upwardly they slide past the contacts so that contact 78 rests on the vertical arm of one contact element 77 and contact 79 rests on the adjacent right hand insulating block 76 thus breaking the all-metal path between them. Each pair of these contacts 78, 79 constitute a bifurcated contact 80 of which a series are provided, and are mounted adjacent to each other across the machine, and are insulated from one another, there being one such element for each denominational order on each printing unit such as the applicant is describing. Thus, each horizontal contact element 77, has resting thereon one leg each (78 and 79) of two separate bifurcated contact elements 80. A lever 81 is pivotally mounted adjacent each contact 78 which rests opposite the vertical leg of the contact element 79. This lever is adapted to be manually rocked counterclockwise to cam said contact 80 out of contact with the contact element 77, and hold it out of engagement until manually released. For the present, only the printing and elimination of zeros in connection with numerical listing will be considered.

When a perforation is encountered by the lower brushes in one of the index point positions from 0 to 9, the magnet 18 (Fig. 1) is energized and the lever 58 is rocked counterclockwise as explained, moving the arm 72 from under the arm of the bell crank 73 allowing it to drop and rotate the bell crank in a counterclockwise direction until the contact element 77 is held against a contact bar 82 which extends clear across the machine. This bar is suitably mounted on the framework of the machine and is insulated therefrom. This contact bar also acts as a limit stop for the movement of all the bell cranks 73. When the bell crank 73 is released in the manner just explained, the contacts 78 and 79 of two of the adjacent elements 80 are resting with contact 78 on the vertical leg of contact element 77 and contact 79 on the adjacent insulated block 76 so there is no circuit established between the two adjacent elements 80. It will be noted in Figs. 2 and 10 that the left hand contact 78 of the two cooperating with element 77 is the one that will rest on the insulating block, so that should this figure be the extreme left hand significant figure of a number the bell crank lever 73 corresponding to the column of that particular figure will be the extreme left hand bell crank to be released and as its corresponding contact member is raised, the insulating block on that member breaks the circuit for all contacts 80 to the left so that no circuit is established through any of those contacts to the left to the printing magnet. This will be explained in detail later. A bail 83 extending across the machine is integral with the bail 70 and rocks counterclockwise striking an extension on bell crank 73 to unlatch it on top of the

arm 72 which is being restored at the same time by the bail 70.

It will be noted that all balls shown in the drawings are shown in their restored positions.

5 As previously stated, all columns in the card which do not have a digit punched therein are punched at the zero index point position as shown in Fig. 6. This applies to numerical fields—in the alphabetical fields the columns not used for 10 letters are left blank.

The zero printing operation is not initiated by the lower brush encountering a perforation in the zero index point position but is initiated by a zero impulse which occurs every card cycle and is initiated by zero contact 85 closing by means of a controlling cam 86 once each card cycle in synchronization with the passage of the zero index point position under the lower brushes 45. In order to do this and avoid back circuits the lower 20 brushes 45 are cut out from the printing magnets 18 during the passage of the zero position on the card past the brushes. This is accomplished by commutators 88 which are fixed to a shaft 89 extending across the machine and suitably journalled in the frame thereof. Fixed to the shaft 89 is a gear 90 which meshes with a gear similar to gear 18 and fixed to drive shaft 10 so that the commutator 88 makes one third revolution per card cycle. The development of one of 30 these commutators 88 is shown in Fig. 9. There are three brushes *a*, *b*, and *c* on each of these commutators. Brush "*a*" is double and wipes on both tracks of the commutator, brush "*b*" on one track of the commutator and makes contact with the metallic segment "*b*" at the same time that brush "*a*" does. This segment passes under brushes "*a*" and "*b*" as the brushes 45 traverse the zero index point position in the card.

Brush "*c*" wipes the other track of the commutator and makes contact with the metallic segment "*c*" at the same time that brush "*a*" does. Brushes "*a*" and "*c*" wipe this segment while the brushes 45 traverse the 9 to 1 index point positions on the card.

45 Referring now to Figs. 10 and 6, let it be assumed by way of example that account No. 9025 is to be listed. There are two zeros at the extreme left of the field that are perforated and must be suppressed in printing. There is one zero in the 50 hundreds position which must be printed, and all zeros to the right of the units or last figure in the number must be suppressed. The columns to the right of this last digit, namely columns 55 22, 23, 24, etc., as shown in Fig. 6, must be used for other purposes and therefore must be split off from the other field. Cards 100 are stacked 60 in the magazine and are fed one by one in the usual well known manner past the brushes 31. The circuit through these brushes is only in 65 condition to be established during the time when the 0, 11, and 12 index point positions on the card pass the brush 31, by the closure of contact 101 under control of cam 102 during that interval. In the example given there are zero 70 perforations in card columns 16, 17, and 19 (Fig. 6). When these perforations pass the brushes 31 the magnets 19 corresponding to these columns will be energized and the selecting lever 28 will be arrested with the catch 30 in the zero 75 notch and the corresponding step 39 will engage the block 40 to retract the sector 41. No delay in the printing action will occur, however, as the sector 41 is cut away in back of the block and in the plane of movement of the hooked arm 41 so that it will immediately drop far enough

to actuate the type hammer as soon as it is released at the zero position.

The circuit just referred to is from one side of the line 103, through card lever contacts 104, now closed, brushes 31, line 105, magnets 19 to the other side of the line 106. The machine is started in the usual manner by closing start key 107 and closing a circuit from line 106 through start key 107, relay magnet 108, stop key 109 (normally closed), driving motor 110, to line 103. 10 When relay magnet 108 is energized, relay contacts 111 close to establish a stick circuit through the motor. The start key is held until the cards start passing the lower brushes when card lever contact 112 is closed, completing a circuit from 15 line 106, through start key 107, contact 111, wires 113 and 114, make and break contact 115, card lever contacts 112, magnets 116 and 117, wire 118 to the other side of the line 103. Energization of magnet 117 completes the motor stick circuit as relay contacts 119, and cam contacts 120, bridge the start key 107. As make and break contacts are timed to break during the time between cards when there is no card under the brushes 45, the relay 117 will become deenergized and open contacts 119. The cam contact 120, however, is timed to close during that short interim which continues to hold the circuit through the motor and thus keep the machine continuously operating. As the card continues 30 past the lower brushes 45, the perforation in the 9 index point position in the thousands denominational order (in the assumed example) will act to close a circuit from line 106, wire 114, contacts 115, relay contact 121 (now closed), wire 122, 35 brushes 45, brushes "*c*" and "*a*" of commutator 88 (which are electrically connected during the time that 9 to 1 on the card pass brushes 45), magnet 18, to line 103, thus tripping the magnet 40 18 in the thousands order and releasing the corresponding hammer 66 to strike the type character "9" as explained.

The corresponding lever 73a is released as previously explained to move the contact element 71a upward with its corresponding insulated 45 block 76a to take the position as indicated at A in Fig. 2. The units order printing mechanism will be released as the "5" indicating point position passes the brushes 45 and the tens order will be effected as the "2" indicating point position passes the brushes, so that their corresponding contact element 71 will also take the positions as shown at C and D, respectively (Figs. 2 and 10). The hundreds order has a zero perforated therein but is not effected by the brush 55 45 as the commutator 88 will have moved to a position at the zero point in the cycle where brushes "*a*" and "*c*" are not electrically connected but instead brushes "*a*" and "*b*" are electrically connected (Figs. 10 and 9). This connection is effective while the zero point on the card is passing the brush 45. The zero control contact 85 is timed to be operated by cam 86 so as to close as the zero point position on the card passes the brush 45, to send an impulse through the following circuit: line 106, wire 114, contacts 115 (now closed), contacts 121 (closed), contacts 85 (closed), contact bar 82, contact elements 77 that may be resting against contact bar 82 at that time and such bifurcated contacts 80a to 80e inclusive as may be in electrical circuit at that time, which conditions will be explained later. From the bifurcated contacts 80a to 80e the circuit is closed at this time through brushes "*a*" and "*b*" on the commutators 88a to 88e and 75 88f.

from thence the impulse is sent to the magnets 18.

Only those magnets corresponding to digits to the right and including the extreme left hand significant figure receive these impulses for reasons to be explained later, thus those magnets 18 which have already received an impulse to release their corresponding type, however, to effect the printing of a numeral, will not again effect a printing operation since the bail 70 has not yet relatched the levers 58. The magnets 18 corresponding to those columns having a zero perforation will not have been affected up to this time and this zero impulse will now energize these magnets only which correspond to columns perforated at the zero position to the right of the first left hand significant figure, to effect zero printing but the columns to the left will have the zero printing suppressed in a manner which will now be explained.

Continuing with the assumption that the number 9025 is to be printed. Referring to Fig. 2, A represents the elements coating with the thousands order of the number, B with the hundreds and C and D with the tens and units order respectively. As previously described, by the time the card has passed the brushes 45 so that the zero index point position has reached the brush, the elements corresponding to A, C, and D have been released and their corresponding contact elements 77 are making contact with the contact bar 82.

Contact element 77b has not been released since no impulse has yet been transmitted to its corresponding magnet and therefore said element is not in contact with bar 82. When the zero printing impulse is initiated by the closure of zero contact 85 as previously described, the impulse is transmitted through bar 82 to contact element 77a (now in contact with bar 82) to the left hand bifurcation of contact 80b as viewed in Figs. 2 and 10 and from thence through the commutator 88b to the printing magnet 18 to effect the printing of zero. If the next digit to the right, i. e. the tens digit, was also zero, then the element 77 at C would not be tripped against bar 82. The zero impulse would then travel from the left hand bifurcation of contact 80b to the right hand bifurcation across the horizontal leg of contact element 77 at B to the right hand bifurcation of the contact 80c and thence through its corresponding commutator 88c to the magnet 18. Thus the impulse may be carried right on down to the right to print as many zeros as there are.

The zero impulse is blocked from traveling to the left, however, since the contact element 77 corresponding to the left hand significant figure has been tripped bringing the insulated portion 76 into contact with its contact 80, thus in the example, contact element 77a has moved upward and the right hand bifurcation of contact 80c is now resting on the insulated portion 76a so that the zero impulse transmitted over the bar 82 cannot be communicated to contact 80a and therefore cannot be carried across to the next left hand contact element 77. Thus the printing of all zeros to the left is suppressed.

Referring now to the lever 81 previously mentioned. One purpose of these levers is to split the printer. In the example given as shown in Fig. 6, six columns of the card have been allotted to the field for "Account No.", namely, columns 16 to 21, inclusive. The fields to the left and right of this field are allotted to other data and

therefore must be split off from the possibility of being effected by any of the entries into the "Account No." field as well as itself being effected by any entries in the adjacent fields. Thus in the present case, the lever 81 (Figs. 1, 2 and 10) adjacent to the left hand bifurcation of the contact element corresponding to the sixteenth column of the card will be rocked counterclockwise (as viewed in Fig. 2) to cam said contact arm out of cooperation with the contact element 77 corresponding to the fifteenth column in the card and the lever 81 cooperating with the left hand bifurcation of contact 80e corresponding to the twenty-second column of the card will be moved to cam this arm out of cooperation with the contact element 77 at D which corresponds to the twenty-first column in the card. Thus, for example, the zero impulse transmitted through the bar 82 to contact element 77 at D cannot be carried through the contact 80e to the right of the last column and effect zero printing all the way along the printer.

Plugging arrangements are provided in the circuits from brushes a and c of the commutators 88 as shown at 150, 151, and 153. For use in fields of the record card where zero suppression is desired a jumper or connector 152 is inserted between plug sockets 150 and 151 to bring the commutators 88 into operative connection in the circuit of the magnets 18 corresponding to the last columns in the field set aside for this purpose.

When a field in the record card is to be used for alphabet printing as well as numerical printing such as street addresses and numbers or code numbers with both numerals and letters, it is desired to eliminate the zero suppression and to print all characters indicated on the record card. In such event, only such columns as indications are to be printed from are perforated; the rest are left unperforated as shown in Fig. 6 in the field including columns 1 to 15 wherein two columns to the extreme left and two to the extreme right of the field are blank as the name perforated in the field did not contain sufficient letters to fill the field. To eliminate the zero suppression feature, the circuit is broken between the brushes 45 and the commutators 88 by removing the connecting cords 152 between plug sockets 150 and 151, and providing instead a connecting cord 154 plugged into plug sockets 150 and 153 so that the circuit from the analyzing brushes 45 is shunted around the commutators 88 direct to the magnets 18. In addition thereto, levers 81 are rocked clockwise as shown in Fig. 10 (counterclockwise as shown in Fig. 1) to cam the left contact finger of the contacts 80 out of contact with the contact element 77, there being a lever 81 for each contact 80.

This breaks the circuit from zero impulse contact 85 so that no zero impulses can be transmitted to magnets 18. Thus, as seen from the above, all printing impulses are initiated directly from the record card through brushes 45, plug sockets 150, connectors 154, plug sockets 153 to the magnets 18.

Fig. 7 shows a modification of the zero suppressing mechanism. Lever 58 corresponds with lever 58 in Fig. 1 and cooperates with its coating lever 48 and actuating wheel 64 when said lever 58 is released by the latch 125 which is turned about its pivot 126 by the pull of the magnet 18 on its armature 56 when energized. The bail 70 operates in the same manner as previously explained to relatch the levers 58. The bail 127 running transversely of the machine, supports a

series of bell crank levers 128, pivoted at 129 and biased in a clockwise direction by a spring 130. There is one of these levers for each denominational order of the printer. The magnets 18 receive impulses as the cards pass the brushes 45 (Fig. 10). With the use of this modification the commutators 88, contact bar 82, contacts 80, contact elements 77 and zero impulse contacts 85 are eliminated, for in this instance the magnets 18 are operated directly from the brushes 45 so that there is a direct connection of wires from each brush 45 to each magnet 18, thus zero perforations in the card send their impulses direct to the magnets 18. The elimination of zeros is accomplished by mechanical blocking as herein-after described, instead of breaking the circuit to the magnets as shown in the preferred embodiment.

When the magnet 18 is energized it pulls the latch 125 clockwise releasing the lever 58 which is rotated in a counterclockwise direction by spring 131 to effect printing in the manner as previously described. The end of lever 58 then rests against the bail 70, the end of said lever abutting the flat surface 132 of the lever 125 and holding it in its moved position so that the hooked end 133 is held adjacent to and under the arm 134 on the bell crank lever 128 thus preventing said levers from dropping when the bail 127 may lower. On each of the levers are pivotally mounted levers 135 having ends 136 extending at right angles and intercepting the plane of the next lever 128 adjacent thereto to its right as viewed in Fig. 8. Thus lever 135 on the hundreds denomination has its end 136 extending across the plane of lever 134 of the tens denomination T. There is provided a shoulder 137 on lever 128 under which the extension 136 of the lever 135 to its left (Fig. 7) extends. Thus it will be seen that if the extreme left hand lever 128 is held up the extension 136 of lever 135 affixed to that lever, will support the shoulder 137 of the next to the right holding it up, and it in turn will hold the next right hand lever and so on. Thus any lever 128 held up will hold up all adjacent levers to its right. The lever 135 is pivotally mounted on its lever 128 so that it may be swung counterclockwise to swing the extension 136 out of cooperative relationship with the next lever 128 at its right so that it will not be effected thereby.

Let it again be assumed that the number 9025 is to be printed. The levers 125 corresponding to the thousands, tens and units denominational orders will be released before the zero index point position reaches the brush 45.

This means that the hooked ends 133 of these levers will have moved under the arms 134 of each corresponding bell crank lever 128. Just prior to the zero impulse or as the brushes 45 pass from the 1 to the zero index point position on the card, the bail 127 is timed to lower and all bell crank levers 128 supported by it will tend to rock clockwise under the action of spring 130. Those bell crank arms corresponding to the levers 125 which were previously tripped cannot lower because of the fact that the hooked end 133 is under the arm 134 and will support the bell crank lever. Thus in the example cited the bell crank lever 128 corresponding to the thousands denominational order (9 of the number) will be held up, and by means of the extension 136 will hold up the adjacent bell crank lever 128 corresponding to the hundreds denominational order (0 of the number) whereas the levers to the left of the

thousands denominational order will lower with the bail 127 so that the arm 134 will fall in front of the hooked ends 133. The bail 127 will have lowered when the zero index point position of the cards pass the brushes 45 and send out impulses from these columns which are perforated at that position. In the example shown in Fig. 6, there are zero perforations in card columns 16, 17, and 19, making two to the left of the number to be printed which must be eliminated, and one within the number which must be printed. As the bail 127 is lowered at the time the zero impulses come from these card columns it will be seen that the levers 128, which are not held up by the previous tripping of the levers 125 as explained, will have lowered so that their arms 134 will rest immediately in the path of the hooked end 133.

This prevents lever 125 from being rocked clockwise by the zero impulse to the magnet 18 thus preventing the printing of zeros on those columns so blocked, thus suppressing the zeros to the left of the left hand digit "9" in the example. The digit "0" in the hundreds position, however, is printed since the lever 128 corresponding to this position will be held up by the extension 136 on the lever 128 corresponding to the thousands denominational order position which in turn is held up by the lever 125 which was previously tripped when the figure "9" of the number was printed.

The purpose of levers 135 is for splitting the printer so as to prevent zeros from being printed to the right of the unit number 5 of the number 9025, the lever 135 on the units order will be swung counterclockwise thus removing the end 136 from interfering with the next right hand lever 128 so as not to prevent it from lowering and obstructing the printing of zeros in the next adjacent field where desired.

A series of latches 138 is pivotally mounted on the machine and each one is adapted to be moved into position so that the hook 139 engages the hook 140 to latch up its corresponding bell crank lever 128 to render it inoperative. These are provided where it is not desired to suppress any zero printing which occurs for example, where it is desired to print alphabet and numerals as previously mentioned or where it is desired to print straight code numbers which often carry zeros to the left of the significant figures, such as for example 001, 011, etc.

The contacts 155 (Fig. 10) controlled by cam 86 are for the purpose of sending an impulse each printing cycle to the magnet 156 for the purpose of spacing the paper after each printing operation. As this has no part in the present invention and as the operation of the paper spacing mechanism is fully shown and described in my copending application previously mentioned, it is deemed unnecessary to make any further explanation thereof.

While all the fundamental novel features of this invention have been shown and described and pointed out it will be understood that various omissions and substitutions and changes in the form and details of the device illustrated and in its operation may be made by those skilled in the art without departing from the spirit of the invention. I intend to be limited therefore only as indicated by the scope of the following claims.

What is claimed is as follows:

1. In a printing machine, a plurality of continuously moving type carriers each having a plurality of type spaced thereon, a printing ham-

mer, means for impelling said hammer against one of said elements while in motion to effect printing thereby, means for suppressing operation of said impelling means with respect to certain type and means for rendering said suppressing means inoperative at will.

5 2. In a card controlled printing machine, a plurality of continuously rotatable type carriers each having a plurality of type spaced thereon, 10 printing hammers, a power actuator, coupling means for connecting said power actuator with said printing hammers to effect printing, tripping means for controlling the operation of certain of said coupling means and other tripping means controlled by the first named tripping means for 15 controlling the operation of certain other of said coupling means.

20 3. In a record controlled printing machine, a plurality of type elements, printing hammers, a power actuator, coupling means for connecting said power actuator with said printing hammers to effect printing, means controlled by the record for effecting operation of certain of said coupling means, and means other than the record for effecting operation of others of said coupling 25 means.

30 4. In a printing mechanism, a type carrying member having a plurality of type elements thereon continuously moving through printing position, a hammer, a power actuator for impelling said hammer against one of said type elements to effect printing, means for selectively coupling said power actuator with said hammer at any printing position of said type elements and means for selectively suppressing the 35 operation of said last named means in certain printing positions.

40 5. In a record controlled printing machine, a plurality of type carrying members each having a plurality of digit type and a zero type continuously moving through printing position, a plurality of hammers, power actuating mechanism, coupling means for selectively connecting said hammers with said power actuating mechanism, record reading means for selectively controlling said coupling means at any of the printing positions of the digit type elements and means for rendering the record reading means

ineffective in its position corresponding to the zero type printing position.

5 6. In a record controlled printing machine, a plurality of continuously rotating type carriers having a plurality of type elements thereon, a plurality of hammers, power actuating mechanism, coupling means for connecting said hammers with said power actuating mechanism, tripping means for effecting connection of said coupling means with said hammers and actuator, 10 record controlled means for selectively controlling said tripping means, other tripping means controlled by said first mentioned tripping means, and means controlled by said last mentioned tripping means for controlling said record control means. 15

20 7. In a record controlled machine, record analyzing means, a printing device including a plurality of groups of type, a plurality of hammers, a power actuator and coupling means for connecting said hammers to said actuator, tripping means for controlling said coupling means, electrically controlled devices for selectively controlling said tripping means, circuits for connecting said electrically controlled devices with said record analyzing means, other tripping means controlled by said first named tripping means, electric contacts controlled by said second mentioned tripping means, circuits for connecting said electrically controlled devices with said contacts and cyclically operated switching means common to both mentioned circuits for periodically switching the electrically controlled devices from said record analyzing means to said contacts. 25 30 35

40 8. In a record controlled printing machine, a plurality of groups of types having a plurality of digit types and a zero, means for effecting printing by the digit type comprising a plurality of hammers, a power actuator and coupling means for connecting said power actuator to said hammer, a trip for controlling said coupling means, and means for suppressing zero printing comprising a bail, a lever supported by said bail and adapted to be lowered adjacent to said trip 45 whereby said trip is rendered ineffective to control said coupling means. 45

EUGEN BUHLER.
